UNITED STATES PATENT OFFICE.

LEO STEIN AND CLAYTON F. WETMORE, OF HOBOKEN, NEW JERSEY, AS-
SIGNORS TO THE NATIONAL CASKET COMPANY, OF SAME PLACE.

DESIGN FOR A CASKET.

SPECIFICATION forming part of Design No. 28,916, dated June 21, 1898.

Application filed February 28, 1898. Serial No. 672,096. Term of patent 14 years.

To all whom it may concern:

Be it known that we, LEO STEIN and CLAYTON F. WETMORE, citizens of the United States, residing at Hoboken, county of Hudson, and State of New Jersey, have invented and produced a new and original Design for Caskets, of which the following is a specification.

Our invention relates to designs for casket-bodies, having more particular reference to the shape of the shell as a unitary design.

It consists, essentially, of a casket having circular ends and flat corners, all of which is substantially illustrated in the accompanying drawings, in which—

Figure 1 shows an isometrical view of our design of casket. Fig. 2 is a transverse longitudinal section on line X X, Fig. 1. Fig. 3 is a similar view on line y y.

In carrying out the design we employ moldings encircling the base of the shell and also at the upper edge thereof.

a is the body. b is the flat corner.

Having described our invention, what we claim, and desire to secure by Letters Patent, is—

The design for a casket, substantially as herein described and shown.

Signed by us, at Hoboken, State of New Jersey, this 16th day of February, 1898.

LEO STEIN.
CLAYTON F. WETMORE.
